UNITED STATES PATENT OFFICE

2,193,611

BELT BUCKLE

Dorsey M. Wirth, Bucyrus, Ohio

Application January 17, 1939, Serial No. 251,366

6 Claims. (Cl. 267—71)

This application relates to expanding belt buckles, and the object of this invention is to provide a belt buckle wherein an elastic tensioning means is provided between the buckle and the end of the belt attached thereto for allowing the expansion and contraction of the belt while in position around the waist of the wearer. Another object of this invention is to produce a means for attaching a belt end to this particular style of buckle without it being necessary to retain the spring and yoke parts of the buckle between the belt and its folded back end, and thereby eliminate excessive thickness at this point. By my novel invention the belt end can be attached to this buckle and secured in its natural flat way.

In the drawing:

Figure 1 is a front view of one form of spring buckle assembly contemplated by this invention.

Figure 2 is a cross sectional view of Figure 1.

Figure 3 is a front view of another form of spring buckle assembly in this invention.

Figure 4 is a cross sectional view of Figure 3.

Figure 5 is a perspective view of another form of spring buckle assembly in this invention.

Figure 6 is a perspective view of the part 7 as used in the assembly of Figure 5.

Figure 7 is a front view of one of the buckle frames used in this invention.

Figure 8 is a perspective view of the belt connector used in this invention.

In Figure 1 the buckle frame 1 has a cross bar 6, swingably carried on the cross bar 6 is the belt hole engaging tongue 2, the connecting member 7 is carried on the cross bar 6, the ends R and S of the yoke 3 are connected with the connecting member 7, carried on the yoke 3 is the spring 4, the belt connector 5 is slidably carried on the yoke 3 through the openings H and M, the belt E is attached to the connector 5. The spring 4 resists the longitudinal movement of the belt connector 5 on the yoke.

In Figure 3 the buckle frame 11 has swingably mounted on one side of the frame the belt hole engaging tongue 12, the connecting member 17 is carried on the same side of the buckle frame, the ends R and S of the yoke 3 are connected with the connecting member 17, carried on the yoke 3 is the spring 4, the belt connector 5 is slidably carried on the yoke through the openings H and M, the members A and D are bands clamped around the side of the buckle frame to retain in position the connecting member 17, the belt E is attached to the connector 5, the spring 4 resists the longitudinal movement of the belt connector 5 on the yoke.

In Figure 5 the buckle frame 1 has a cross bar 6, the connecting member 27 has bent fingers B and C that are connected with the cross bar 6, the extended parts Y and Z are formed into barrel shape eyes, through these eyes are carried the end portions R and S of the yoke 3, carried on the yoke 3 is the spring 4, the belt connector 5 is slidably carried on the yoke through the openings H and M, the belt E is attached to the connector 5, the spring 4 resists the longitudinal movement of the belt connector on the yoke.

In Figure 6 is shown the connector 27 as used in Figure 5, showing the fingers B and C, and the barrel shaped eyes Y and Z.

In Figure 7 is shown a buckle frame which consists of the buckle body T, and having arms O, these arms are bent into yoke formation and the ends of the arms meet as at P.

This form of buckle may be used in the buckle assembly of Figure 3. In Figure 8 is shown the belt connector 5, showing the openings H and M, through which the yoke slides in the different forms of assembly in the drawing.

The buckle frames of the various forms described in this invention can be made by forming a bar or wire into shape as desired, or the buckle frame can be stamped from a flat piece of material, or the buckle frame may be casted.

Other parts of this invention can be formed into shape by use of bars or wire, or they may be stamped from flat material, or they may be casted.

It is definitely understood that I do not desire to limit this application of this invention to the particular modifications set out herein to illustrate the principles thereof, and any changes may be made in material and structure and arrangement of parts consistent with the spirit and scope of this invention.

I claim:

1. A belt buckle of the class described comprising a buckle frame, and a belt connector assembly, said belt connector assembly comprising a yoke having the end portions of the member forming the yoke connected with the buckle frame by means of a connecting member, a belt connector provided at one end with openings and a belt connecting portion at the other end, said connector slidably carried by the yoke through said openings, a spring on the yoke cooperating with the belt connector for resisting longitudinal movement of the connector on the yoke, and a belt hole engaging tongue swingably carried by said buckle frame.

2. A belt buckle of the class described comprising

35

50

55

- ing a buckle frame having a cross bar, and a belt connector assembly, said belt connector assembly comprising a yoke having the end portions of the member forming the yoke connected with the said cross bar by means of a connecting member, a belt connector provided at one end with openings and a belt connecting portion at the other end, said connector slidably carried by the yoke through said openings, a spring on the yoke cooperating with the belt connector for resisting longitudinal movement of the connector on the yoke, and a belt hole engaging tongue swingably carried by said cross bar.
3. A belt buckle of the class described comprising a buckle frame having a cross bar, and a belt connector assembly, said belt connector assembly comprising a yoke having the end portions of the member forming the yoke connected with the said cross bar by means of a connecting member, the connecting member having sleeve formations, the yoke having its end portions carried in said sleeve formations, a belt connector provided at one end with openings and a belt connecting portion at the other end, said connector slidably carried by the yoke through said openings, a spring on the yoke cooperating with the belt connector for resisting longitudinal movement of the connector on the yoke, and a belt hole engaging tongue swingably carried by said cross bar.
4. A belt buckle of the class described comprising a buckle frame, and a belt connector assembly, said belt connector assembly comprising a yoke having the end portions of the member forming the yoke connected with the buckle frame by means of a connecting member, the connecting member having sleeve formations, the yoke having its end portions carried in said sleeve formations, a belt connector provided at one end with

openings and a belt connecting portion at the other end, said connector slidably carried by the yoke through said openings, a spring on the yoke cooperating with the belt connector for resisting longitudinal movement of the connector on the yoke, and a belt hole engaging tongue swingably carried by said buckle frame.

5. A belt buckle of the class described comprising a buckle frame, and a belt connector assembly, said belt connector assembly comprising a yoke having the end portions of the member forming the yoke connected with the buckle frame by means of a connecting member, said connecting member pivotally connected with the buckle frame, a belt connector provided at one end with openings and a belt connecting portion at the other end, said connector slidably carried by the yoke through said openings, a spring on the yoke cooperating with the belt connector for resisting longitudinal movement of the connector on the yoke, and a belt hole engaging tongue swingably carried by said buckle frame.

6. A belt buckle of the class described comprising a buckle frame having a cross bar, and a belt connector assembly, said belt connector assembly comprising a yoke having the end portions of the member forming the yoke connected with the said cross bar by means of a connecting member, said connecting member pivotally connected with the cross bar, a belt connector provided at one end with openings and a belt connecting portion at the other end, said connector slidably carried by the yoke through said openings, a spring on the yoke cooperating with the belt connector for resisting longitudinal movement of the connector on the yoke, and a belt hole engaging tongue swingably carried by said cross bar.

DORSEY M. WIRTH.
